United States Patent

Des. 234,476

Patented Mar. 18, 1975

234,476

STOOL

Irving M. Rosen, White Plains, N.Y., assignor to The Pace Collection Inc., New York, N.Y.

Filed Jan. 24, 1973, Ser. No. 326,391

Term of patent 14 years

Int. Cl. D6—01

U.S. Cl. D6—35

FIG. 1 is a perspective view of a stool according to the invention;

FIG. 2 is a plan view of the stool;

FIG. 3 is a bottom view of the stool; and

FIG. 4 is a side view of the stool, the opposite side view being identical.

I claim:

The ornamental design for a stool, as shown.
